UNITED STATES PATENT OFFICE

MILTON S. DUNKELBERGER, OF DAYTON, OHIO

DESIGN FOR A FISH BAIT

Application filed July 6, 1931. Serial No. 40,430. Term of patent 7 years.

To all whom it may concern:

Be it known that I, MILTON S. DUNKELBERGER, a citizen of the United States, residing in the city of Dayton, in the county of Montgomery and State of Ohio, have invented a new, original, and ornamental Design for a Fish Bait, of which the following is a specification, reference being had to the accompanying drawings, forming part thereof.

Figure 1 is a perspective view of a fish bait, and Figure 2 is a cross sectional view taken through the back of the bait looking toward the head, showing my new design.

I claim:

The ornamental design for a fish bait, as shown.

MILTON S. DUNKELBERGER.
